Primary Examiner — Mitchell I. Siegel

(57) **CLAIM**

The ornamental design for a throwing device, as shown and described.

DESCRIPTION

FIG. 1 is a perspective view of the throwing device according to the invention, showing the back and side of the throwing device.

FIG. 2 is a perspective view of the throwing device according to the invention, showing the front and side of the throwing device.

FIG. 3 is a back view of the throwing device.

FIG. 4 is a left side view of the throwing device.

FIG. 5 is a front view of the throwing device.

FIG. 6 is a right side view of the throwing device.

FIG. 7 is a top view of the throwing device; and,

FIG. 8 is a bottom view of the throwing device.

The broken lines are for the purpose of illustrating the environment of the article only and form no part of the claimed design.
